UNITED STATES PATENT OFFICE.

FRANK J. DIACONT, OF PROVIDENCE, RHODE ISLAND, ASSIGNOR TO WILLIAM BENS, OF SAME PLACE.

DESIGN FOR A HANDLE FOR BUTTON-HOOKS OR SIMILAR ARTICLES.

SPECIFICATION forming part of Design No. 29,017, dated July 12, 1898.

Application filed June 7, 1898. Serial No. 682,855. Term of patent 3½ years.

To all whom it may concern:

Be it known that I, FRANK J. DIACONT, a citizen of the United States, residing at Providence, in the county of Providence and State 5 of Rhode Island, have invented and produced a new and original Design for Handles for Button-Hooks or Similar Articles, of which the following is a specification, wherein reference is made to the accompanying drawing, o and the letters thereon, which forms a part of this application, and which shows the article in elevation, and together furnish a clear and exact description of my design, which is essentially as follows:

5 The leading feature of my design is a handle for button-hooks and similar articles ornamented with a panel inclosed by foliates and surmounted by a crown. More particularly described, it consists of a group of stems o a a, the longer members of which, b b, expand to form the outer contour of the handle-body. The stems b b burst into two sets of foliates c c, which with the foliated stem terminations

d d slightly overlap the main panel x. A lower panel e, with a row of beads h h on either side, 25 is embraced by the stems a a. The upper portion of the handle-body is ornamented by converging foliated scrolls surmounted by small circles in relief. The handle terminates in a crown composed of several acute arches 30 k k, at the junction of each of whose bases with the circlet o is a trefoil p. At the summit of the crown is a ball m, flanked by rows of smaller balls n n.

Having thus described my invention, what 35 I claim as new, and desire to secure by Letters Patent, is—

The design for a handle for button-hooks or similar articles, substantially as herein shown and described. 40

In witness whereof I have hereunto set my hand.

FRANK J. DIACONT.
